UNITED STATES PATENT OFFICE.

PAUL DAIMLER, OF CANNSTATT, GERMANY, ASSIGNOR TO THE FIRM DAIMLER-MOTOREN-GESELLSCHAFT, OF UNTERTURKHEIM, GERMANY.

REGULATING MECHANISM FOR COMBUSTION ENGINES.

Application filed August 7, 1920, Serial No. 402,067, and in Germany August 5, 1918.

(GRANTED UNDER THE PROVISIONS OF THE ACT OF MARCH 3, 1921, 41 STAT. L., 1313.)

This invention relates to an adjusting device intended for folding connections with internal combustion engines having a compressor providing the engine with an additional charge of air after the throttle valve of the carburetter has been opened in a certain degree.

An important feature in the arrangement and combination of parts constituting the invention resides in making the operation of the compressor dependent upon the throttle valve of the carburetter having been adjusted previously thereto, because otherwise, if the two admission members would be adjusted independent from one another, it might occur that the compressor be made to deliver the compressed air into the carburetter at an improper time which might have, under circumstances, hurtful consequences for the power engine, as well as for the machine or machines driven by it.

Now, according to this invention, the carburetter and the compressor are actuated and adjusted one after the other with aid of the co-operation of a spring or an equivalent member inserted into the common actuating member for the carburetter and the compressor or forming a part of this member. A part of the adjusting device for the throttle valve of the carburetter is held fast after it has covered a certain path in the direction in which said valve is opened; then on that common actuating member being further moved in the same direction, the operating rod for the valve in question is extended or elongated and at the same time another rod displaces a sleeve forming an annular slide which shuts an aperture provided in the connection pipe between the

compressor and the carburetter. Up to this moment the air which the compressor delivered had escaped into the atmosphere through that aperture, but as soon as this latter is closed by the sleeve or slide, the air is forced through the carburetter into the working cylinder or cylinders of the engine.

In order to make my invention, more clear, I refer to the accompanying drawing in which Fig. 1 is a diagrammatical illustration of an adjusting device constructed according to this invention, and Fig. 2 shows some parts of it in another position.

The motor *a* is connected with the compressor *b* which, in its turn, is connected with

the carburetter *d* by a pipe *c*. The throttle valve *d'* of the carburetor is connected with an operating rod *e* which in turn is connected with an operating lever *h* fulcrumed at *g*. The connection between the rod *e* and lever *h* is such that the latter is capable of a further movement after the actuations of the throttle valve *d'* and its rod *e* have been arrested at a predetermined point; in the illustrated example this result is attained by providing a spring *f* in the connection from the rod *e* to the lever *h*. The latter is connected also with a rod *i* attached at its other end to a sleeve *k* forming an annular slide and being so arranged upon the pipe *c* as to be adapted to close and open an aperture *c'* provided in the pipe *c*.

The manner of operation of this combination and arrangement of parts is as follows:

Supposing, the lever *h* which is the common operating member for the rods *e* and *i* have been turned along its guide quadrant from the position *x* into the position *y*, the throttle valve *d'* of the carburetter *d* is open in a certain measure; further opening of said throttle valve *d'* is prevented by providing suitable means to arrest the operation of the rod *e* at a predetermined point. On moving the lever *h* from the position *y* into the position *z* the rod *e* or its spring respectively, is extended or elongated, but the rod *i* draws the sleeve or slide *k* over the aperture *c'* of the pipe *c*. Owing to the communication of this pipe with the atmosphere being now interrupted, the air delivered by the compressor is forced into the carburetter and thus to and into the working cylinder or cylinders of the internal combustion engine.

When moving the lever *h* back from the position *z* into the position *y*, the aperture *c'* is opened, but the position of the throttle valve *d'* is not yet altered, because merely the spring *f* contracts. Only when the lever *h* is further moved back from the position *y* to the position *x*, also the throttle valve *d'* is again actuated, viz., closed.

Having thus particularly described the nature of my invention, what I claim as new and desire to secure by Letters Patent of the United States is:

1. The combination of an internal combustion engine including a carburetor, a throttle valve for said carburetor, a source of com-

pressed air connected with said carbureter, means for controlling the passage of compressed air to said carbureter, an operating lever and connections extending from said lever to said throttle valve and said compressed air controlling means respectively, said connections being such as to operate the throttle valve to a predetermined point and to permit a subsequent independent movement of the operating lever to independently actuate said compressed air controlling means.

2. The combination of an internal combustion engine including a carbureter, a throttle valve for said carbureter, a source of compressed air connected with said carbureter, means for controlling the passage of compressed air to said carbureter, an operating lever, a non-extensible connection between said lever and said compressed air controlling means and an extensible connection between said lever and said throttle valve whereby the latter is operated to a predetermined point after which said connec-

tion is extended by a further operation of 25 said lever to operate said compressed air controlling means without producing any further operation of said throttle valve.

3. The combination of an internal combustion engine, including a carbureter, a 30 throttle valve for said carbureter, a compressor connected with said carbureter and the atmosphere, a valve for controlling the flow of compressed air and for selectively diverting it to the carbureter or to the atmosphere, an operating lever, a rod connecting the latter with said compressed air valve, a rod connected with said lever and throttle valve and a spring in the latter connection to permit an extension thereof by a 40 continued operation of said lever after said throttle valve has been operated to a predetermined point and to cause said compressed air valve to be actuated independently of said throttle valve.

45 In testimony whereof I affix my signature.

PAUL DAIMLER.
